United States Patent Office

Des. 215,205

Patented Sept. 16, 1969

215,205

HOTDOG STAND

Norman Mumford, % The Beach Sands, 17970 Gulf
Blvd., Redington Shores, Fla. 33708

Filed Aug. 30, 1968, Ser. No. 13,351

Term of patent 14 years

Int. Cl. D25—04

U.S. Cl. D13—1

FIG. 1 is a front elevational view of a hotdog stand, showing my new design.

FIG. 2 is a rear elevational view thereof.

FIG. 3 is a top view thereof.

FIG. 4 is an end view thereof, both ends being identical.

I claim:

The ornamental design for a hotdog stand, as shown.
